COMBINED REEL AND HANDLE UNIT

Morris E. Wood, Bronson, Mich., assignor to Bronson Specialties, Inc., Bronson, Mich., a corporation of Michigan

Filed Nov. 13, 1961, Ser. No. 67,481

Term of patent 14 years

(Cl. D31—4)

FIGURE 1 is a side elevational view of a combined reel and handle unit showing my new design;

FIGURE 2 is a top plan view thereof; and

FIGURE 3 is a front elevational view thereof.

That side of the reel opposite to the one shown in FIGURES 1 and 2 is provided with a plate closing off such side as distinguished from the one which carries the bearing and crank.

The side not shown is like the side shown, except that the plate member is plain as indicated in FIGURES 2 and 3.

The ends of the handle and reel not shown are plain and unornamented.

I claim:

The ornamental design for a combined reel and handle unit, as shown and described.
